Letters Patent No 141887-Dated Aug 16th 1863.

Design for the Plates of a Stove.

The schedule referred to in these Letters Patent and making part of the same.

to all whom it may concern:

Be it known that I, Nicholas S. Geddes, of the City of Troy, in the County of Rensselaer, and State of New York, have invented or produced a new and original ornamental Design for Stove Plates; and I do hereby declare that the following is a full and exact description of the same, reference being had to the accompanying photographic drawing of a stove plate embodying my said ornamental design:

This ornamental design consists of a plain, convex surface of three-lobed leaves, e. g. a fruit cluster, side bands and leaf scrolls, g. a dependent piece; and fruit, holder, j. b. all shaped and combined together and arranged in the middle part of a plain surface panel, of a stove plate, so as to present the appearance represented by the photographic drawing hereto annexed.

What I claim as new and of my invention or production and desire to secure by Letters Patent, is The herein described ornamental design for a stove plate.

In testimony whereof I hereunto set my hand this twenty-ninth day of June, eighteen hundred and sixty four.
